VAPORISATION OF LIQUEFIED GASES

John Forrest, Cockfosters, England, assignor to The British Oxygen Company Limited, a company of Great Britain

Filed Sept. 29, 1959, Ser. No. 843,091

Claims priority, application Great Britain Sept. 29, 1958

2 Claims. (Cl. 62—53)

This invention relates to the vaporisation of liquefied gases of low boiling point and more particularly to a method of reducing pressure surging in tube type vaporisers for the vaporisation and superheating of such liquefied gases.

By the term "liquefied gases of low boiling point" is meant liquefied gases boiling at 1 atmosphere pressure at temperatures below ambient and particularly below -150° C. Examples of such liquefied gases are liquid oxygen, liquid nitrogen and liquid methane.

A widely used method of vaporising liquefied gases of low boiling point and superheating the gas so formed to atmospheric temperature consists in passing the liquefied gas through a tubular vaporiser in heat exchange relationship with a warm fluid surrounding the tubes. The tubes are usually mounted with their axes vertical, the liquefied gas being pumped to the lower end of the tubes and gas superheated to atmospheric temperature being withdrawn from the top of the tubes.

It is known that in tubular vaporisers, when the tube diameter is increased beyond a certain limit, the phenomenon known as pressure surging occurs. It is not possible, at economic flow rates to avoid the surging under such conditions. Pressure surging, that is to say ebullition in the vaporiser, is spasmodic and the pump delivery pressure and the temperature of the vaporised gas leaving the vaporiser both fluctuate violently. The phenomenon also produces considerable noise and vibration of the vaporising coil and its connecting pipework. Alternative methods of avoiding pressure surging would be to use an increased number of tubes with reduced diameters, or to raise the pressure of the liquefied gas above the critical pressure of the fluid followed by a reduction in such pressure after evaporation. Both alternatives have obvious disadvantages.

It is an object of the present invention to provide a method of reducing pressure surging in such vaporisers.

It is a further object to provide a vaporiser of this type in which pressure surging does not substantially occur in use.

According to one aspect of the present invention, a method of reducing pressure surging during the vaporisation and superheating of liquefied gases of low boiling point as hereinbefore defined by heat exchange with a fluid whose temperature is substantially higher than that of said liquefied gas in a tube type vaporiser, comprises packing the section of the tube or tubes in which evaporation of the liquefied gas takes place with randomly disposed packing elements.

According to another aspect of the present invention, a tube type vaporiser for the vaporisation and superheating of liquefied gases of low boiling point as hereinbefore defined by heat exchange with a fluid whose temperature is substantially higher than that of said liquefied gas and having a reduced tendency to pressure surging in use has the section thereof in which evaporation of the liquefied gas takes place packed with randomly disposed packing elements.

2

The packing elements may be any of the well-known elements used for the random packing of gas-liquid contact devices, for example, Raschig rings or McMahan saddles. The packing elements are preferably made of metal. Their size will depend on the diameter of the vaporiser tube. Thus for a tube of diameter 2 inches, Raschig rings of $\frac{3}{4}$ inch diameter are a suitable packing. The density of packing is preferably at least 60% by which is meant that the actual number of rings used are about 60% of the maximum number which it is possible to contain in the tube when randomly packed and tamped down.

The packing promotes turbulence in the vaporising section of the vaporiser and reduces spasmodic ebullition. 15 Fluctuations of the pump delivery pressure and the temperature of the gas leaving the vaporiser are substantially reduced and there is a considerable reduction in noise and vibration from the tube or tubes and the associated piping. The flow through the packed vaporiser 20 is very smooth and its output is appreciably increased. This increase may be as much as 20%.

The precise length of the tube which requires to be packed in accordance with the present invention will depend on the diameter of the tube, the pressure and 25 throughput of liquefied gas and the particular liquefied gas being vaporised. Thus, for liquid oxygen at a pressure of 30 p.s.i.g. and using steam at 40 p.i.s.g. for heating, then the surface area of the packed section will be approximately 0.53 sq. ft. per 10,000 s.ft.³ per hour of 30 oxygen evaporated. For liquid nitrogen and liquid methane, the corresponding figures are 0.43 and 0.68 respectively.

It is essential in packing the vaporiser in accordance with the present invention that the evaporating section 35 should be substantially completely packed, since if only a part of this section is packed, pressure surging will still take place. To illustrate this, experiments were made with a single tube vaporiser for liquid oxygen under conditions such that the length of the evaporating section 40 was between 4 and 6 feet. The packing was $\frac{3}{4}$ inch Raschig rings. With a packed section of length 4 ft. at 70% packing density and a pump suction pressure of 9 p.s.i.g., the pump delivered pressure was 40 p.s.i.g. fluctuating ± 5 p.s.i.g. with peaks of 50 p.s.i.g. The temperature of gaseous oxygen leaving the vaporiser was 20° C. $\pm 20^{\circ}$ C. and was difficult to control. The output of 45 the vaporiser was 59,000 s.ft.³/hr. of oxygen.

With the vaporiser packed for a length of 6 ft. at 63% 50 packing density, the pump delivery pressure was steady at 40 p.s.i.g. and the temperature of the oxygen leaving the vaporiser was steady at 20° C. The output was 62,500 s.ft.³/hr.

Packing of the vaporiser beyond the evaporating section does not further reduce pressure surging but it increases the pressure drop through the vaporiser and this 55 may cause a substantial drop in throughput.

The invention will now be described with reference to the accompanying drawings in which

Figure 1 shows diagrammatically a circuit for the 60 vaporisation of a liquefied gas incorporating a vaporiser according to the present invention; and

Figure 2 shows diagrammatically a part of the vaporiser of Figure 1 in more detail.

Referring to Figure 1, the liquefied gas is stored within 65 a thermally insulated vessel 10 from the bottom of which it passes through a line 11 to a pump 12 where it is pumped to any desired pressure below the critical pressure of the gas. The liquefied gas is then passed by line 13 to an evaporator and superheater consisting of a single tube 14 wound in a helix through which the liquefied gas 70 is passed, enclosed in a vessel 15, through which a heat-providing fluid such as steam is passed by means of an

inlet 16 and an outlet 17. In the tube 14, the liquefied gas is first evaporated and the vapour so formed superheated by heat exchange with the heat-providing fluid, the superheated vapour leaving by a line 18.

The tube 14 is shown diagrammatically in greater detail in Figure 2. The liquefied gas enters at a bottom inlet 19 and leaves as superheated vapour through the top outlet 20. In accordance with the invention, the section of the tube 14 in which vaporisation of the liquefied gas occurs is packed with randomly arranged packing elements indicated at 21. These elements are retained within the vaporisation section of the tube 14 by means of retaining devices 22, 23 in the form of perforated cone-shaped metal plates located at each end of the vaporisation section. The superheating section comprises the remainder of the tube 14, the upper retaining device 23 being located at the point along the tube 14 where evaporation of the liquid is complete.

I claim:

1. A method of reducing pressure surging during the vaporisation and superheating of a liquefied gas of low boiling point by heat exchange with a fluid whose temperature is substantially higher than that of said liquefied gas in a tube-type combined vaporiser and superheater comprising packing only that section of the tube or tubes in which evaporation of the liquefied gas takes place to

4
a packing density of at least 60% with randomly-disposed, hollow, geometrically-shaped, metal packing elements of the type used for randomly packing gas/liquid contact devices.

5 2. A tube-type combined vaporiser and superheater for the vaporisation and superheating of liquefied gases of low boiling point by heat exchange with a fluid whose temperature is substantially higher than that of said liquefied gas having only that section of the tube or tubes thereof in which vaporisation of the liquefied gas takes place packed to a packing density of at least 60% with randomly disposed, hollow, geometrically-shaped, metal packing elements of the type used for randomly packing gas/liquid contact devices, whereby pressure surging is reduced during use.
